REAR VIEW MIRROR FOR VEHICLES

James W. Holzman, Haycock Township, Bucks County, Pa., assignor to Delbar Products, Inc., Perkasie, Pa.

Filed June 19, 1972, Ser. No. 264,252

Term of patent 14 years

Int. Cl. D12—16

U.S. Cl. D12—187

FIG. 1.

FIG. 3.

FIG. 2.

FIG. 4.

FIG. 6.

FIG. 5.

FIG. 1 is a top plan view of a rear view mirror for vehicles showing my new design;

FIG. 2 is a front elevational view thereof;

FIG. 3 is a left side elevational view thereof.

FIG. 4 is a right side elevational view thereof.

FIG. 5 is a rear elevational view thereof; and

FIG. 6 is an enlarged sectional view taken along line 6—6 of FIG. 5.

I claim:

The ornamental design for a rear view mirror for vehicles, substantially as shown.
